DESIGN FOR A SET OF PLAYING CARDS

Frederick Crompton, Central Falls, R. I.

Application April 3, 1933. Serial No. 47,681

Term of patent 14 years

To all whom it may concern:

Be it known that FREDERICK CROMPTON, a citizen of the United States, residing at Central Falls, in the county of Providence and State of Rhode Island, has invented a new, original and ornamental Design for a Set of Playing Cards, of which the following is a specification, reference being had to the drawing forming a part thereof.

The drawing represents face views from a set of playing cards illustrating my new design, which

set contains five suits of thirteen cards each, including a fifth suit of which the 10, 9, 8 and Ace are shown. The same scheme of ornamentation is carried throughout the thirteen cards of said fifth suit, the other four suits being conventional.

I claim:

The ornamental design for a set of playing cards substantially as shown and described.

FREDERICK CROMPTON.
